US00D751627S

(12) **United States Design Patent**
Warner

(10) **Patent No.:** **US D751,627 S**
(45) **Date of Patent:** **** Mar. 15, 2016**

(54) **CAMERA CALIBRATION TOOL**

(71) Applicant: **LUCASFILM ENTERTAINMENT COMPANY LTD.**, San Francisco, CA (US)

(72) Inventor: **Paige Warner**, San Francisco, CA (US)

(73) Assignee: **LUCASFILM ENTERTAINMENT COMPANY LTD.**, San Francisco, CA (US)

(**) Term: **14 Years**

(21) Appl. No.: **29/503,920**

(22) Filed: **Sep. 30, 2014**

(51) **LOC (10) Cl.** **16-05**

(52) **U.S. Cl.**

USPC **D16/250**

(58) **Field of Classification Search**

USPC D10/61, 64, 65, 70; D14/217, 238.1, D14/239, 481, 483; D16/202, 219, 220, D16/230, 237-250; 250/252.1; 348/148, 348/187, 188; 356/243.1; 382/154; 396/443

(57) **CLAIM**

The ornamental design for camera calibration tool, as shown and described.

DESCRIPTION

FIG. 1 is a perspective view of a camera calibration tool showing a first embodiment of my new design; FIG. 2 is a rear perspective view thereof;

FIG. 3 is a side elevational view from a left side thereof;

FIG. 4 is a side elevational view from a right side thereof;

FIG. 5 is a side elevational view from a front side thereof;

FIG. 6 is a side elevational view from a rear side thereof;

FIG. 7 is a top plan view thereof;

FIG. 8 is a bottom plan view thereof;

FIG. 9 is a perspective view of a camera calibration tool showing a second embodiment of my new design; and,

FIG. 10 is a rear perspective view thereof.

The broken lines in the figures depict portions of the camera calibration tool that form no part of the claimed design.

1 Claim, 10 Drawing Sheets
